C. E. LOOFBOURROW, OF OAKLAND, CALIFORNIA.

SEMAPHORE SAFETY-ALARM.

No. 872,843.

Specification of Letters Patent.

Patented Dec. 3, 1907.

Application filed July 10, 1906. Serial No. 325,484.

To all whom it may concern:

Be it known that I, GEORGE LESLIE PETTYGROVE, a citizen of the United States, and resident of Berkeley, county of Alameda, 5 State of California, have invented certain new and useful Improvements in Semaphore Safety-Alarms, of which the following is a specification.

In the operation of railroad trains semaphores are extensively used to pass and stop trains at stations. Two semaphore arms are usually employed, one signaling to west bound trains, the other to east bound. Both these arms are normally set to the 15 "stop" position, which is at right angles to the axis of the supporting pole; and trains are passed by lowering these arms so as to cause them to make an acute angle with the lower part of the pole, the meaning of this position being "clear". A third position is provided for, in which the arm is raised to form an obtuse angle with the lower part of the supporting pole, the meaning of this position being "proceed with caution"; but this 25 third signal is seldom used, and is taken no account of herein.

Semaphore arms are operated by levers working in slotted arcs situated in a handy position for the operator. The levers normally stand upright at the center of the arc, which maintains the semaphore arms in their horizontal "stop" position. When approaching trains whistle for passing signals if the operator has no orders for them he 30 throws the appropriate lever to "clear", and returns it to "stop" as soon as the train has passed. But it sometimes happens that the operator under pressure of business forgets for the moment that he has orders for the 35 particular train, and inadvertently displays the "clear" signal, only realizing his mistake 40 when the train has passed beyond his control.

The object of my invention is to provide means of fixing in the mind of the operator 45 the fact that orders are on hand for delivery, and to make that fact the subject of his attention at the very instant when the question of "stop" or "clear" is being settled by him.

50 I attain my object by means illustrated in the accompanying drawing, of which

Figure 1 is a side elevation, partly in section, of the signal levers and arc of a semaphore apparatus; Fig. 2 is a plan view of 55 same; Fig. 3 is a diagram of electrical con-

nctions, with a view of the spring hooks for holding the train order clip boards.

Similar numerals of reference refer to similar parts throughout the several views.

In general terms my invention consists in 60 providing means of giving to an operator at the instant that he moves a semaphore signal from its stop position, an audible alarm, whenever he has an undelivered train order on hand; and of means of audibly impressing 65 continuously on his mind, when he is passing one train that should properly be cleared, the fact that he has orders for other trains. These audible signals may be of any desired character; but those that appear most suitable are a vibrating bell and a buzzer. The bell and buzzer are so connected that they are both electrically actuated by moving either lever off the "stop" position, whenever undelivered train orders are on hand; 70 and the buzzer alone is actuated to give continuous warning, when, train orders being on hand, trains are being properly cleared.

In detail my invention consists of the various combinations and elements of old and new character shown in the accompanying drawing, or rather of such novel parts thereof as are claimed in the subjoined claims.

1 is a lever operating the west arm of a semaphore apparatus, 2 a lever operating the 85 east arm, and 3 the slotted arc aforesaid.

I provide a plurality of hooks 4, 5, 6, adapted to suspend the clipboards 7, 8, 9, said clipboards securing the blanks used for copying train orders, said hooks being movable to make and break electrical contacts. When all the clipboards are suspended from the hooks, the weight thereof keeps the electrical contacts open; but when any one of said clipboards, as 7, is removed, the contacts of said hook are closed by a spring 10 90 each of said hooks being similarly provided with a spring.

The spring hook contacts are in circuit with a bell 11 and a buzzer 12, and also with 100 battery 13; and included in said circuits, in a manner shown in Fig. 3, and fully described below, are buttons 14, 15, 16, 17, 18, 19 on the semaphore arc. The buttons on said arc control electrical contacts in circuit with 105 said bell and buzzer, or bell, or buzzer, and these contacts are all so arranged as to be opened by downward pressure on the buttons, and closed by upward pressure of the springs shown at 20, 21, and 22. 110

Semaphore levers are equipped with latches 23, 24, which engage notches 25, 26, 27, in the arc, to hold said levers in position. To these latches I attach devices 28, and 29, adapted to act on buttons aforesaid by pressing them downward, and separating their contacts.

Referring now to the circuit diagram, Fig. 3, and bearing in mind the described apparatus, the operation of my device will readily be understood. When all the clipboards are on their hooks, which marks a condition characterized by the absence of undelivered train orders, both the bell circuit and the buzzer circuit are open at the hook contacts. The levers may therefore be operated in any desired manner without operating the alarm. But if a clipboard is removed from any one of the hooks, which marks a condition characterized by the presence of an undelivered train order, a hook contact is closed. Whereupon the movement of either lever, releasing the downward pressure on the arc buttons, closes the button contacts, and closes the circuit through the bell, or the buzzer or both. So, also, if either lever is in the "clear" position, the removal of a clipboard will close the buzzer circuit, and thus admonish the operator to adjust his semaphore properly.

Consider now the case of both levers being in their upright, "stop" position. Suppose the clipboard 7 is off hook 4, and a train order is awaiting delivery. If the operator should move lever 1 from its upright position, circuits through bell and buzzer are completed as follows: from battery 13 through closed contacts of hook 4, to bell 11, to closed contacts of button 15, to closed contacts of button 17, to battery; and from battery to closed contacts of hook 4, to buzzer 12, to closed contacts of button 14, to battery. Consider now the case of levers being in position

shown in the drawing. Both bell and buzzer circuits are open at hook contacts. Remove 45 clipboard 7 from hook and a circuit is completed through buzzer, through contacts of hook 4, and contacts of button 19; but the bell circuit is open at button 16 by downward pressure of device 28.

Having described my invention, what I claim as new, and desire to secure by Letters Patent of the United States, is:

1. A semaphore safety alarm comprising the combination with a semaphore of an electrical alarm bell circuit and an electrical alarm buzzer circuit, said circuits being normally open at two points, means of closing said circuits at one of the points by the act of removing a train order clipboard from 55 its normal position, means of closing said circuits at the other point by the act of moving said semaphore from its "stop" position, and means of opening said bell circuit by the act of setting the semaphore to "clear" position.

2. In a semaphore safety alarm, means for suspending train order clip-boards comprising movable hooks, electrical contacts thereon separable by the weight of said clip-boards, and a spring on every hook adapted 70 to close its contacts when a clip-board is removed.

3. In a semaphore safety alarm, a semaphore lever, means for signaling an imminent 75 danger alarm and a cautionary signal alarm at the instant of removing said lever from stop position, and means for stopping said imminent danger alarm, situated at clear position.

In testimony whereof I have signed my name in the presence of two witnesses.

GEORGE LESLIE PETTYGROVE.
